(57) **CLAIM**

The ornamental design for an overload relay, as shown and described.

DESCRIPTION

FIG. 1 is a perspective view of overload relay.

FIG. 2 is a front view of overload relay.

FIG. 3 is a rear view of overload relay.

FIG. 4 is a right side view of overload relay.

FIG. 5 is a left side view of overload relay.

FIG. 6 is a top plan view of overload relay; and,
FIG. 7 is a bottom view of overload relay.The broken lines in the drawings illustrate portions of an
overload relay that form no part of the claimed design.**1 Claim, 7 Drawing Sheets**(56)
